UNITED STATES PATENT OFFICE.

ROBERT E. LEE, OF CINCINNATI, OHIO.

GRAVITY-FEED BOTTLE COOLING AND DISPENSING CABINET.

Application filed November 9, 1926. Serial No. 147,282.

My invention relates to improvements over the construction set forth in my co-pending application, Serial No. 98,467, filed March 30, 1926.

5 The objects of this invention are to provide simple, efficient, convenient and easily operated means for removing the bottles one at a time from within the cabinet.

Another object of this invention is to provide means of this character which insures easy withdrawal of the bottles and tends to prevent more than one bottle to be withdrawn at a time.

The invention consists in providing an 15 upwardly and outwardly inclined wall positioned adjacent the lower ends of the bottle guideways; in providing a plurality of slots which receive ears on the lower ends of said guideways adapted to be bent 20 against the outer surface of said wall whereby the walls of said guideways are securely fixed thereto in spaced apart relation with one another; in providing a downwardly projecting wall or partition between the extended front of the cabinet and the rear portion thereof of sufficient length to extend below the ice-water line within the cabinet, thus helping to retain the cool air within 25 the cabinet and keep the hot air out of the main part of the cabinet when using the lower serving door for the removal of the bottles for use.

The invention also consists in the peculiar 35 construction, combination, location and arrangement of parts, as herein set forth and claimed.

In the drawings:

Fig. 1 is a side elevation of a cabinet embodying my invention, parts shown in section and by dotted lines;

Fig. 2 illustrates the lower portion of one of the bottle guideways, the outwardly adjacent inclined wall being shown by dotted lines;

45 Fig. 3 is an enlarged view of the parts shown in the circle in Fig. 2;

Fig. 4 shows a front elevation of the inclined wall which is partly broken away, two of the bottle guideways, and the manner of attaching the guideways to the inclined wall;

50 Fig. 5 is an isometric view of one of the elevated bottle tracks (which are inserted between the walls of the bottle guideways at their lower ends);

55 Fig. 6 is a vertical cross-section taken on

a plane corresponding to line 6—6 of Fig. 3;

Fig. 7 is a vertical cross-section taken on a plane corresponding to line 7—7 of Fig. 3;

Fig. 8 is a horizontal cross-section taken 60 on a plane corresponding to line 8—8 of Fig. 4;

Fig. 9 is a plan view of the reinforcing strips used on the lower ends of the bottle guideways before bending; and 65

Fig. 10 is a fragmentary side elevational view showing the lower end of one of the partitions, six bottles, one of the inclined strips, and the inclined wall, the last two named parts appearing in vertical section. 70

In the embodiment of my invention as illustrated and which shows a preferred construction I provide a bottle cooler and automatic feeder which comprises cabinet 1, ice compartment 2 and bottle guideways 3. 75

15 In my earlier constructions the lower ends 4 of guideways 3 were attached directly to the front wall 5 of cabinet 1. With such construction considerable difficulty was experienced in removing the end bottle 7, due to the weight thereagainst of the other bottles. Such construction also resulted in withdrawing bottle 8 along with bottle 7 and, of course, this was objectionable.

In my present construction, inclined wall 85

6 is provided near its top with rivet holes 9 and also a plurality of vertical slots or openings 10, as clearly shown in Fig. 4. The ends 4 of guideways 3 are provided with ears 11 which are adapted to pass through slots 10

in inclined wall 6 and then bent or clinched over, as shown in Figs. 1, 8 and 10, respectively. After all of the bottle guideways 3 are attached to inclined wall 6 in this manner, the upper end 12 of said wall is then

securely fastened to front wall 5 as by rivets 13 passing through holes 9 in said inclined wall and holes 14 in said front wall 5, as

clearly illustrated in Fig. 1. The lower side 90 of inclined wall 6 is bent upon itself until the portion 15 is parallel with bottom 16 of cabinet 1.

The outer edge of said portion 15 is bent 95 upward forming rib 17, which rib bears against the inside wall 5 of cabinet 1 and thereby securely holds or supports the guideways 3. Elevated bottle tracks 18 are sub-

stantially the shape shown in Figs. 1, 5 and 10, respectively, the rear portion 19 being provided with holes 20 for the purpose of

receiving bolts or rivets 21 whereby said tracks are securely fastened to bottom 16 100

105

Fig. 5 is an isometric view of one of the elevated bottle tracks (which are inserted between the walls of the bottle guideways at their lower ends);

110 Fig. 6 is a vertical cross-section taken on

of cabinet 1, between each of the bottle guideways 3. The front inclined portions 22 of elevated bottle tracks 18 rest against section 23 of inclined wall 6, as clearly shown 5 in Figs. 1 and 10. At the bottom of bottle guideways 3, I reinforce the upper edge with channelled strip 24, (shown before being bent in Fig. 9), which is bent substantially U-shaped, as shown in the sectional view in 10 Fig. 6. The front edge of each wall of the respective guideways is provided with a channelled member 25 having oppositely disposed lateral flanges 25', as clearly shown in Fig. 7. Said channelled strips 24, together 15 with channelled member 25, are secured to bottle guideways 3 by rivets 26, the strip 24 overlapping the member 25 at their joints.

To prevent warm air from entering and cold air from escaping from the inside of 20 cabinet 1 and ice compartment 2 when horizontal serving door 27 is opened, I provide downwardly extending partition 28 fixed to cabinet 1 by rivets or bolts 29, said partition extending across the entire front of said 25 cabinet and downward below the waterline 30 of ice water 31.

The operation of the device is as follows: Assume that the bottle guideways 3 have been filled, or partially filled, with bottles 30 containing the drinks to be served. Attention is called to the fact that the bottles are inserted within the guideways 3 at the top in a horizontal position. Then note the position of the lower bottle 7 (Fig. 1) and it 35 will be seen that it is resting against inclined wall 6. Should it then be desired to serve bottle 7, simply raise serving door 27 and grasp the neck 7" of bottle 7, as by hand 7" (Fig. 10) and start to pull upwardly. 40 This causes bottle 7 to assume a vertical position, as well as bottle 8, and a few more in the row, in the curved section of the guideway. As the bottle 7 is further pulled upward by hand 7" the weight of the remaining 45 bottles cause said bottle 7 to be pushed forward and at the same time inclined wall 6 forces it upward, as shown in Fig. 10.

As inclined wall 6 is disposed at an angle to the side 7a of bottle 7, the friction between 50 said bottle and said wall is reduced to a minimum, thereby greatly increasing the ease with which end bottle 7 may be removed from the cabinet.

It will be understood that certain changes 55 and modifications in my invention can be made without departing from its scope or spirit as defined in the claims, as for instance, the shape of the inclined wall 6 may vary and instead of being a series of flat 60 portions at different angles to one another, it may comprise a curved wall.

What I claim as new and desire to secure by Letters Patent is:

1. In a bottle cooler and automatic feeder, 65 a vertically disposed bottle guideway curved

at its lower end and each wall having an oblique end with a plurality of ears thereon, flanges on the front edge of said walls to retain said bottles in said guideways to near the lower end thereof and having a bottle 70 exit adjacent said lower end, an upwardly inclined wall across the lower end of said guideway adapted to be secured to said cooler, said inclined wall having slots there- 75 in adapted to receive said ears, which ears will bear against the outer surface of said inclined wall to hold said guideway and inclined wall in fixed relation with each other.

2. In a bottle cooler and automatic feeder, a vertically disposed bottle guideway hav- 80 ing walls and curved at its lower end and having a bottle exit adjacent said lower end, the walls of said guideway being spaced apart in front and rear and having inwardly extending flanges along the edges thereof to 85 retain said bottles in said guideway and forming a slot between the front flanges through which the necks of the bottles extend and each guideway having a bottle exit adjacent its lower end, an upwardly inclined 90 wall at the lower end of said guideways, and an elevated track secured to the bottom of said cooler between the walls of the respective guideways whereby the two end bottles will be raised upwardly to permit ready 95 withdrawal of the end bottle upwardly along said inclined wall.

3. In a bottle cooler and automatic feeder, a vertically disposed bottle guideway hav- 100 ing walls, the front walls of which have spaced apart laterally extending flanges to 105 retain the bottles in said guideway and to permit the necks of the bottles to extend between said flanges, an outwardly inclined wall extending across the lower end of said guideways, and an elevated track between the walls of said guideway curved between its ends, substantially as set forth and for the purposes specified.

4. In a bottle cooler and automatic feeder, vertically disposed spaced apart flanged guideways at front and rear and having a bottle exit near the lower end of said guideways and a U-shaped reinforcing member mounted upon the upper front edge of the respective walls adjacent said bottle exit and having a tapered end extending beneath the flanged portion of each guideway, substan- 115 tially as set forth and for the purposes specified.

5. In a bottle cooler and automatic feeder, a vertically disposed bottle guideway entirely enclosed within said cooler and having a longitudinal slot to permit the necks of the bottles to extend therethrough throughout 125 its entire length and said guideway extending forwardly and downwardly at the lower end of its vertical portion and having a cov- 130 ered bottle exit adjacent its lower end in the wall of said cooler above the end bottles, a

- wall inclined upwardly and outwardly at the lower end of said guideway substantially the length of the bottles and adapted to permit the side of the end bottle to normally 5 rest thereagainst, and when said bottle is drawn to upright position while removing permitting only one lower edge of the bottle to rest against said inclined wall, thereby permitting the bottle to be withdrawn vertically through said exit, the weight of the other bottles assisting in forcing said end bottle vertically along said inclined wall and permitting it to be withdrawn with the greatest possible freedom.
- 10 6. In a bottle cooler and automatic feeder, vertically disposed bottle guideways arranged side by side and each guideway having a longitudinal front slot extending throughout its length adapted to permit the 15 bottles to be inserted horizontally through the front, one at a time upon each other and to extend through said slot while being fed therethrough by gravity and having a covered exit near its lower end to permit the 20 bottles to be withdrawn vertically therethrough, said covered exit being located above the end bottle and an outwardly inclined wall adjacent the lower ends of said guideways to engage the lower edge only 25 of the bottle while being removed.
7. In a bottle cooler and automatic feeder, a vertically disposed bottle guideway having walls extending downwardly and then forwardly in its lower part and having a bottle 30
- exit adjacent the lower end of said guideway, said guideway having a vertically disposed longitudinal slot in its front to permit the necks of the bottles to extend therethrough and retain said bottles within said guideway throughout its length, an upwardly inclined track adjacent the lower end of said guideway, and an upwardly inclined wall at the end of said track and at an angle thereto whereby the two end bottles will be raised upwardly parallel to each other in 35 stacked relation to permit ready removal of the end bottle upwardly along said inclined wall and a cover for said exit in said cooler near said bottle.
8. A gravity feed bottle cooling cabinet 40 provided with a cooling agent and having a bottle chute extending from vertical to horizontal position whereby the bottles are fed therethrough by gravity from parallel horizontal position to parallel vertical position, a covered exit in said cooler adjacent the lower end of said guideway and an inclined wall at the lower end of said guideway whereby the end bottle is readily 45 grasped and drawn by hand to substantially 50 vertical position along said inclined wall and whereby the weight of the other bottles tends to force said end bottle upwardly 55 therethrough when raised to vertical position and thereby assist in the easy withdrawal of the bottle from the cabinet 60 through said exit.
